Primary Examiner — Melanie Pellegrini*(74) Attorney, Agent, or Firm* — Andrew F. Young; Nolte Lackenbach Siegel(57) **CLAIM**

The ornamental design for a jewelry article, as shown and described.

DESCRIPTION

FIG. 1 is a front top perspective view of my jewelry article of the present invention.

FIG. 2 is a rear top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The surfaces are lightly lined for contour. No claim is made to portions of the design which are not shown. The dash-dot-dot lines indicate environmental portions which form no part of the claimed design. The dash-dot-dot lines indicate claim boundary limits to the claimed design.
